tion of Pennsylvania

Application June 11, 1935, Serial No. 25,985

11 Claims. (Cl. 80—53)

Our invention relates to a guide for a rolling mill and, in particular, to a twist guide for a billet mill.

It is customary in rolling billets in stands consisting exclusively of horizontal rolls, to twist the billet 90° between certain of the stands in order to reduce both its cross sectional dimensions. The means heretofore employed for this purpose consists simply of a guide box having a helical passage therethrough adapted to impart a partial twist to the billet as it moves longitudinally through the passage. A billet progressing through a continuous mill has a large momentum because of its mass and speed, and twist guides are therefore subject to very severe usage.

It has been found that the portions of the guide which engage diagonally opposite corners of the billet to effect the twist wear very rapidly, necessitating frequent repair or replacement of the guide. A more serious objection to the twist guides which have previously been used is that particles of hot metal from the billet are picked up by the guide and build up to form sharp points or edges which severely scar the faces of the billets being rolled. While further rolling may "iron out" these scars, they represent inherent defects which are more serious because they cannot be detected externally, and may become apparent only after a great deal of work has been expended upon the material which in that case represents almost a total loss.

We have invented a twist guide for billet mills which avoids the aforementioned objections and provides a novel structure having other features and advantages which will become apparent as the detailed description thereof proceeds and will be particularly pointed out in the appended claims.

In accordance with our invention, we provide a twist guide comprising a pair of opposed similar guide blocks, each of which has a hole therethrough and helical grooves extending along the inside and outside of the blocks from the hole to one end thereof. Roller chains designed particularly to withstand the severe usage to which twist guides are subject, lie in the grooves, traverse the holes and extend around the ends of the blocks. The chains are constructed to permit them to follow the helical grooves without overstraining the parts thereof. The rollers of the chains are adapted to be engaged by a billet passing longitudinally through the guide and the shape of the grooves is such that the rolls follow

a path which effects a partial twisting of the billet before it reaches the next stand.

For a complete understanding of the invention, reference is made to the accompanying drawings illustrating a present preferred embodiment thereof, although it will be understood that the invention may be otherwise embodied within the scope of our broader claims. In the drawings—

Figure 1 is a side elevation of the guide showing the rolls of a stand in a continuous billet mill in section;

Figure 2 is a plan view of the guide with a portion removed;

Figure 3 is an end elevation as would be seen by looking from the right in Figure 1;

Figures 4, 5 and 6 are sectional views taken respectively along the lines IV—IV, V—V and VI—VI of Figure 1;

Figure 7 is a developed partial longitudinal sectional view;

Figure 8 is an end elevation of the entering end of the guide as would be seen by looking from the left in Figure 1;

Figure 9 is a plan view of a part of the guide;

Figure 9a is a side elevation thereof;

Figure 10 is a plan view of a portion of the roller chain;

Figure 11 is a side elevation thereof, and

Figure 12 is a sectional view along lines XII—XII of Figure 11.

Referring now in detail to the drawings and, for the present, to Figures 1 through 8, the twist guide of our invention comprises a pair of guide blocks 10 and 11 having matching feet 12 by 35 which they are positioned relatively to each other to form a guide housing. The blocks 10 and 11 are identical and only one of them will be described in detail. The block 10 has a hole 13 extending therethrough adjacent one end. The 40 entering end of the block is provided with a helical surface 14 adapted to engage a billet indicated at 15 as it enters the guide and start the twisting thereof. The guide blocks 10 and 11 are mounted in a convenient manner adjacent the 45 exist side of the rolls 16 of one stand of a continuous billet mill. Conveniently, the guides may be supported on a rest bar and may be wedged or otherwise secured therein. A support of the kind generally used for twist guides of the previous types can easily be adapted to receive the guide of our invention.

Outer and inner grooves 17 and 18 extend from a point adjacent the hole 13 longitudinally of the block 10 toward the exit end thereof. The 55

inner groove 18 is preferably helical, the pitch being such as to cause a 90° twist of the billet by the time it reaches the next stand of rolls. Ordinarily, the entire length of the guide would be only approximately one-third or one-fourth of the distance between stands. The outer groove 17 may be straight. The intersection between the grooves and the hole 13 is rounded to provide a guiding surface 19. Adjacent the exit end of the guide, the block 10 is provided with a member 20 having a similar guide surface. The member 20 is adjustably mounted on the end of the block by means of studs 21, to provide a take-up for a roller chain 22.

15 The chain 22 lies in the grooves 17 and 18 and is trained around the guiding surface 19 and the member 20. A top plate or bridge 23 is secured to the block 10 and has a hole 24 therein adapted to be disposed in alignment with the hole 13 through the block 10. The bridge 23 has a helical guiding surface 25 adapted to overlie the outer groove 17. The block 10, furthermore, is provided with outwardly and inwardly extending guide flanges 26 and 27 constituting the continuations of the outer walls of the grooves 17 and 18.

20 The roller chain 22 in traversing the inner helical groove 18 is effective to twist the billet progressively as shown in Figures 4 through 6, after the twist has been initiated by the surfaces 14 adjacent the entering end of the guide. In Figures 1 and 2, only the center line of the chain has been shown at 22', since if the chain were shown there in full, it would obscure the view of the other parts of the guide. The bridge 23, furthermore, is omitted in Figure 2 for the sake of further clearness in illustration. Figure 7 is obviously not a true section, but is a view taken along a surface following the helical twist imparted to the chain by the shape of the inner groove 18. Figure 3 illustrates the path of the chain in dotted lines at 22".

25 The chain 22 is composed of a plurality of rolls 28 connected by links 29 and pivot pins 30 extending through the links and the rolls. The pins 30 are headed at one end as at 31. The under side of the head 31 is in the shape of a truncated cone 32. Washers 33 with beveled edges are disposed between the links 29. The pins 30 are secured in place by cotter pins 34. The latter are protected by caps 35 on the ends of the pins 30, against abrasion on the side walls of the grooves 17 and 18. The caps 35 also transmit end thrust received thereby directly to the pin 30, thus avoiding any tendency for the pins 30 to shear off the pins 34. The edges of the caps 35 are beveled as at 36. The cone shaped portions 32, the beveled edges 36 and the beveled-edge washers 33 provide sufficient lost motion between the various parts of the chain to permit the chain to be twisted through a considerable angle in a relatively short length. The chain is thus adapted to follow the helical grooves without overstraining any of its parts.

30 The operation of the invention will probably be apparent from the foregoing description of its structure. As the billet enters the guide from the rolls 16 with its sides vertical, the leading end is partially twisted by the surfaces 14. It then engages the rolls 28 of the chains 22 and as the latter traverse the passages 18, they progressively force the billet to twist through an increasing angle. The amount of twist in the travel of the chains, of course, is proportional

to their length relative to the total distance between adjacent mill stands.

35 The twisting effect is continuous so that the leading end of the billet continues to turn relative to that portion still in the rolls 16, even after the leading end of the billet has left the exit end of the guide. By the time the leading end of the billet reaches the next stand, it has been twisted through substantially 90°. The chains 22 are driven solely by the frictional engagement thereof by the billet. The rolls 28 transmit the pressure exerted thereon by the billet directly to the guide blocks and the only force on the chain links is the tension necessary to draw the return run thereof back toward the entrance end of the guide. Heating of parts of the guide beyond safe limits is prevented by cooling fluid supplied through nozzles 37.

40 The advantages of our invention over twist guides such as previously employed will be clearly understood by those skilled in the art. Because of the rolls the friction between the advancing billets and the portions of the guide which effect the twisting thereof is reduced to a negligible value and wear on the parts is correspondingly reduced. The chain 22, furthermore, is readily susceptible of lubrication by a grease of appropriate viscosity. There is no tendency, furthermore, for accretions dropped from the hot billets to build up on the chains or other parts of the guide. The scoring or scratching of the billets which has been caused by the guides previously used is thereby avoided, with the result that the quality of the product is materially improved. It is found that the chains and other portions of the guide have a very long life so that the upkeep is almost negligible. The initial cost of the device, furthermore, is not greatly in excess of that of previous types of twist guides.

45 Although we have illustrated and described but one preferred form of the invention, it will be apparent that changes in the construction described and illustrated may be made without departing from the spirit of the invention or the scope of the appended claims.

We claim:

1. A guide for twisting a billet between stands while being rolled in a continuous mill comprising a housing through which the billet is adapted to pass longitudinally, roller chains extending along the housing and adapted to engage diagonally opposite corners of a billet, and helical paths for said chains formed in said housing for so guiding the chains as to twist progressively a billet engaged thereby.

2. A billet twisting guide comprising a housing through which the billet is adapted to move longitudinally, a plurality of rollers connected by links forming a chain movable along a wall of the housing and back along the outside thereof, and helical tracks formed in said housing for said chain whereby the rollers are tilted progressively and twist a billet engaging therewith at its diagonally opposite longitudinal edges.

3. A twist guide for a rolling mill comprising a housing, and traveling roller chain therein effective to impart a twist to a billet passing longitudinally therethrough.

4. The apparatus defined by claim 3 characterized by said housing having a track over which said chain is trained to define a helical surface.

5. A twist guide for a rolling mill comprising a housing, and roll means mounted therein effective to impart a twist to a billet passing longitudinally therethrough, said means including

- a plurality of rolls movable through said housing and connected by links into a chain.
6. A twist guide for a rolling mill comprising a housing adapted to receive a billet from the mill, said housing having a helical groove therein, and a chain traveling in said groove, said chain including rolls adapted to bottom in said groove.
7. A twist guide for a rolling mill comprising a housing adapted to be mounted adjacent the mill to receive a billet therefrom, said housing having a helical groove therein and a chain traveling in said groove, said chain including rolls adapted to bottom in said groove, links connecting said rolls, and means providing for disalignment of the links and the rolls.
8. A twist guide comprising a housing having a helical groove therein and a chain traveling in said groove, said chain including rolls adapted to bottom in said groove, links connecting said rolls and bevel edge washers assembled with said links and rolls.
9. A twist guide for a rolling mill comprising a housing adapted to be mounted adjacent the mill to receive a billet therefrom, said housing having a helical groove therein and a chain traveling in said groove, said chain including rolls adapted to bottom in said groove, links connecting said rolls, pivot pins traversing said rolls and links, said pins each having a head on one end and caps removably secured to the other ends of the pins.
10. A twist guide comprising a guide block, a hole therethrough, helical grooves extending along both sides of the block from the hole toward one end of the block, and a roller chain lying in said grooves, traversing said hole and extending around one end of the block.
11. The apparatus defined by claim 10 characterized by a take-up for said chain adjustably carried on the block.
